UNITED STATES PATENT OFFICE.

EUGENE A. DE LAN, OF NEW CASTLE, PENNSYLVANIA, ASSIGNOR TO SHENANGO POTTERY COMPANY, OF NEW CASTLE, PENNSYLVANIA, A CORPORATION OF PENNSYLVANIA.

DESIGN FOR A PLATE.

Application filed August 16, 1928. Serial No. 27,834. Term of patent 7 years.

To all whom it may concern:

Be it known that I, EUGENE A. DE LAN, a citizen of the United States, and residing at New Castle, in the county of Lawrence and State of Pennsylvania, have invented a new, original, and ornamental Design for a Plate, of which the following is a specification, reference being had to the accompanying drawings, forming a part thereof, which is a plan view of a plate embodying my new design.

I claim:

The ornamental design for a plate, substantially as shown.

EUGENE A. DE LAN.
